DESIGN FOR A COMBINATION SINK AND COOKING STOVE

Charles C. White, New York, N. Y., assignor to White Cabinet Corporation, New York, N. Y., a corporation of New York

Application January 6, 1945, Serial No. 117,304

Term of patent 14 years

(Cl. D4—2)

To all whom it may concern:

Be it known that I, Charles C. White, a citizen of the United States, residing in New York city, in the county of New York and State of New York, have invented a new, original, and ornamental Design for a Combination Sink and Cooking Stove, of which the following is a specification, reference being had to the accompanying drawing, forming part thereof.

sink and cooking stove, showing my new design;

Figure 2 is a perspective view of the same taken from a position at an angle of 45° to the Figure 1 showing; and

I claim:

The ornamental design for a combination sink and cooking stove, substantially as shown.

CHARLES C. WHITE.
